DESIGN FOR A HANDBAG

Samuel R. Goldsmith, New York, N. Y.

Application April 6, 1938, Serial No. 76,323

Term of patent 3½ years

To all whom it may concern:

Be it known that I, Samuel R. Goldsmith, a citizen of the United States, and resident of New York city, (Borough of Manhattan), in the county and State of New York, have invented a new, original, and ornamental Design for a Handbag, of which the following is a specification, reference being had to the accompanying drawing, forming a part thereof, and of which Figure 1 is a view in elevation of a handbag showing my new design, and Fig. 2 is a perspective view thereof.

I claim:

The ornamental design for a handbag substantially as shown.

SAMUEL R. GOLDSMITH.
